AUXILIARY CAB FOR A PICKUP TRUCK

Frank Hopkins, Jr., 4770 Fee Road,
Bridgeport, Mo. 63044

Filed Feb. 24, 1972, Ser. No. 229,248

Term of patent 14 years

Int. Cl. D12—16

U.S. Cl. D12—156

FIG. 1 is a perspective view of an auxiliary cab for a pickup truck showing the front, top and right-hand side of my new design.

FIG. 2 is a perspective view showing the rear, top and left-hand side thereof.

I claim:

The ornamental design for an auxiliary cab for a pickup truck, as shown.
